UNITED STATES PATENT OFFICE.

WILLIAM C. GLASS, OF WOONSOCKET, RHODE ISLAND, ASSIGNOR TO UNITED PRINTING MACHINERY COMPANY, OF BOSTON, MASSACHUSETTS, A CORPORATION OF MAINE.

SHEET-FEEDING MECHANISM.

1,275,550.

Specification of Letters Patent. Patented Aug. 13, 1918.

Original application filed November 8, 1912, Serial No. 730,165. Divided and this application filed November 28, 1914. Serial No. 874,550.

To all whom it may concern:

Be it known that I, WILLIAM C. GLASS, a citizen of the United States, and a resident of Woonsocket, Providence county, Rhode Island, have invented an Improvement in Sheet-Feeding Mechanism, of which the following description, in connection with the accompanying drawings, is a specification, like characters on the drawings representing like parts.

This invention relates to sheet feeding mechanisms, and more especially, though not exclusively, to mechanisms for feeding sheets of cardboard into a press which creases and cuts the sheets to make box blanks. This is a division of my prior application for sheet feeding mechanisms, Serial No. 730,165, filed November 8, 1912.

My invention will be best understood by reference to the following specification, when taken in connection with the accompanying illustration of one specific embodiment thereof, while its scope will be more particularly pointed out in the appended claims.

In the drawings:

Figure 1 is a plan of a printing press of common form, having a sheet-feeding mechanism embodying my invention, the parts being shown in the position which they occupy when the press is wide open;

Fig. 2 is a side elevation of the press and the sheet-feeding mechanism, with the parts in the same position as in Fig. 1;

Fig. 3 is a detail plan section, partly broken away, on line 3-3 of Fig. 2, illustrating a portion of the gearing by means of which the sheet-feeding mechanism derives its power from the crank-pin at one side of the press;

Fig. 4 is a side elevation of the press, showing the positions which the parts of the press and sheet-feeding mechanism occupy when the press is closed;

Fig. 5 is a detail side elevation, at an enlarged scale, of a portion of the feed-table and the stop-finger mechanism;

Fig. 6 is an enlarged detail plan section on line 6-6 of Fig. 5;

Fig. 7 is a detail sectional view, partly in elevation, on line 7-7 of Fig. 5;

Fig. 8 is a detail side elevation, at an enlarged scale, of a portion of the sheet-feeding mechanism, illustrating particularly the

first set of grippers and their actuating mechanism;

Fig. 9 is an elevation viewed from the opposite side of the machine from that seen in Fig. 8, illustrating the first set of grippers;

Fig. 10 is a rear elevation of one pair of the first set of grippers;

Fig. 11 is an elevation viewed from the right hand side of Fig. 10;

Fig. 12 is a side elevation of a portion of the sheet-feeding mechanism, illustrating particularly the first and second set of grippers in the relative positions which they occupy when the first is about to deliver a sheet to the second;

Fig. 13 is a detail plan partly in section, illustrating the adjusting means for the changing of the stroke of the second set of grippers;

Fig. 14 is a detail plan at an enlarged scale of one pair of grippers of the second set;

Fig. 15 is a sectional view on line 15-15 of Fig. 14, showing the gripper opening and closing cam in connection with the gripper mechanism;

Fig. 16 is a detail sectional view on line 16-16 of Fig. 14;

Fig. 17 is a detail sectional view on line 17-17 of Fig. 15;

Fig. 18 is a sectional view on an enlarged scale on line 18-18 of Fig. 1, looking toward the left;

Fig. 19 is a detail sectional view on an enlarged scale on line 19-19 of Fig. 1;

Fig. 20 is a sectional view partly broken away on line 20-20 of Fig. 1;

Figs. 21 and 22 are diagrammatic views illustrating the "Whitworth quick return motion" used in connection with the second set of grippers, illustrating the cam in the position which it occupies when the grippers take their maximum stroke;

Figs. 23 and 24 are similar diagrammatic views, illustrating the "Whitworth quick return motion," the cam being illustrated in the position which it occupies when the grippers take their minimum stroke;

Fig. 25 is a diagrammatic view illustrating the "Whitworth quick return motion," in connection with the second and third sets of grippers, the grippers being shown in the relative positions which they occupy at the

moment when the sheet is transferred from the second to the third set. This view illustrates particularly the fact that the variation in the stroke of the second set of grippers

5 takes place beyond the transfer point;

Fig. 26 is a detail plan on an enlarged scale, partly broken away, of the side register mechanism;

Fig. 27 is a side elevation of the side register mechanism illustrated in Fig. 26;

Fig. 28 is a detail sectional view on line 28-28 of Fig. 26;

Fig. 29 is a detail section on line 29-29 of Fig. 27;

15 Fig. 30 is a detail section on line 30-30 of Fig. 26;

Fig. 31 is a detail plan section on line 31-31 of Fig. 27;

Fig. 32 is a detail side elevation of a portion 20 of the sheet-feeding mechanism illustrating particularly the mechanism of the third set of grippers;

Fig. 33 is a sectional view on line 33-33 of Fig. 32;

25 Fig. 34 is a detail plan of one pair of grippers of the third set;

Fig. 35 is a side elevation of the grippers shown in Fig. 34;

Fig. 36 is a detail sectional view at an 30 enlarged scale on line 36-36 of Fig. 1;

Fig. 37 is a detail sectional view at an enlarged scale on line 37-37 of Fig. 1;

Fig. 38 is a diagrammatic view illustrating the first set of grippers about to take 35 the sheet from the feed-table, and showing the second set of grippers holding a previously fed sheet between the platen and the bed;

Fig. 39 is a diagrammatic view illustrating 40 the first set of grippers carrying the first sheet toward the transfer point, where the same is to be transferred to the second set of grippers, this view also illustrating the second set of grippers in the act of transferring to the third set of grippers the sheet which has just been withdrawn from the press by the second set of grippers;

Fig. 40 is a diagrammatic view, illustrating 45 the first set of grippers transferring the first sheet to the second set of grippers, and illustrating also the third set of grippers just dropping the previously creased and cut sheet upon the pile in the sheet-receiving rack, or elevator; and

55 Fig. 41 is a perspective view of a portion of the first and second sets of grippers, illustrating how the shoulders of the first set pass beyond the shoulders of the second set to bring the front edge of the sheet against 60 the shoulders of the second set. In this view, the spring-pressed grippers are omitted for the sake of clearness.

Referring to the drawings, and to the embodiment of my invention which I have 65 there disclosed for illustrative purposes, I

have there shown a press of common form, to which the sheet-feeding mechanism of my invention is applied, I will first briefly describe the press.

Press—(See Figs. 1, 2, 3 and 4.)

70

A frame 1 provides a bed 2, to which a chase 3 is secured. Journalized in suitable bearings in the frame is a main driving shaft 4, the usual fly-wheels being omitted 75 for the sake of clearness. Secured to the shaft are two pinions 5 and 6, meshing with gears 7 and 8, respectively, constituting crank-disks provided with crank-pins 9 and 10. These crank-pins are connected by 80 draw-bars 11 and 12 to eccentric bushings 13 and 14, swiveled on a platen shaft 15, mounted in a platen bridge 16, forming a part of a rocking platen 17, said bushings being connected to each other by a bar 18, 85 by means of which the bushings may be turned in unison upon the platen shaft which passes eccentrically through the bushings. The bar 18 is provided with means of adjustment (not shown) of common 90 form, by which the bushings may be set to vary the strength of the impression at will, or to throw off the impression entirely,

Feed-table and stop-finger mechanism—(See Figs. 1, 2, 4, 5, 6 and 7.)

95

The press may be provided with a feed-table 19, suitably supported thereon above the bed of the press, and serving as a support for a supply of the sheet cardboard, 100 and provided with a plurality of feed-table extensions 19. The feed-table may be provided with side register means, herein a stop 20 of common form, and one or more other stops 21 in the form of fingers, having 105 notched abutments 22, against which the front edge of the sheet may be placed by the operator. These fingers may be secured to a rock-shaft 23, mounted in suitable bearings 24 on the frame of the feed-table. The 110 fingers may be elevated at appropriate times in the operation of the machine by suitable mechanism, herein driven by the press gear 7. Herein there is secured to the rock-shaft 23 an arm 25, having secured thereto a stud 26, located in a slot 27 provided in one end of a link 28, and urged toward the left (Figs. 5 and 6) in said slot by a spring 29, secured at one end to said arm, and at its other end to a pin 30, fixed to the link. This 115 spring provides for a yielding downward pressure of the fingers 21 upon the feed-table extensions, while the arrangement is such that the fingers may be positively lifted to allow the sheet to pass beneath the abutments 22 of the fingers.

The link 28 is herein pivoted at 31 to a cam lever 32, fulcrumed at 33 and having journalized thereon a cam roll 34, actuated by a cam 35 formed in the face of a gear 36 130

journaled on a stud 37. Herein the gear 36 is driven by a pinion 38, secured to one end of a shaft 39, journaled in a bearing bracket 40, and having secured to its other end a gear 41, meshing with the press gear 7. The gears 36 and 38 may be provided with a casing 42, secured to the bracket 40 and the stud 37.

In order to facilitate setting up the mechanism, and adapting it to the press so that the gear 41 will properly mesh with the press gear 7, the bearing bracket 40 may be swiveled on the stud 37, and may be provided with a segmental slot 43, to receive a 15 clamping screw 44. By this means, the pinion 41 may be adjusted with relation to the press gear 7, so as to properly mesh therewith, regardless of inaccuracies and slight differences in presses.

20 *Driving gearing for gripper mechanisms—
(See Figs. 1, 2, 3, 4 and 33.)*

As a convenient means of driving the gripper mechanisms hereinafter described, 25 and timing the same with relation to the press, I preferably employ the driving mechanism which I will now describe. Secured to the crank-pin 9 is a beveled gear 45, meshing with a beveled pinion 46 secured to one end of a shaft 47, while a beveled pinion 48 secured to the other end of the shaft meshes with a beveled gear 49, having secured thereto a spur gear 50, preferably by means of a shear pin 51, designed 30 to shear off, and prevent injury to the mechanism, in the event of any accident which would tend to stop the rotative movement of the gear 50.

Inclosing the beveled gear 45 and pinion 46, is a gear casing 52, which also forms a bearing 53 for one end of the shaft 47. This casing may be swiveled on a hub 54, formed on the gear 45, and may be held against rotation by suitable means, herein a jaw 55, embracing the link 11, the casing being held 45 in place by suitable means, herein a stud 56. Inclosing the beveled gear 49 and pinion 48, is a casing 57, which also forms a bearing 58 for the other end of the shaft 47, as well 50 as a support for a fixed stud or shaft 59 for the gears 49 and 50. Inclosing the gear 50 is a casing 60, swiveled on the stud 59, and held in place thereon by suitable means, herein a washer 61 secured to said stud.

55 The casing 60 may also constitute a support for a gear 62, journaled on a stud 63 and meshing in turn with a gear 64, journaled on a stud 65. The casing 60 may also constitute a housing for the gears 62 and 64. The gear 64 meshes with a gear 66, journaled on a stud 67 secured to a side frame member 68. This side frame member and a similar side frame member 69, both secured to the sides of the platen 17, are 60 rigidly connected to each other by suitable 65

means, herein tie-rods 70 and 71, and form a suitable support at the front of the press for the several gripper mechanisms which will presently be described.

Referring now to the gears 64 and 66, these gears are held in mesh with each other by a link 72, pivoted at its lower end to the stud 65 and at its upper end to the stud 67. Incidentally, this link facilitates the assembling of the parts, inasmuch as it admits of the location of the gear 64 being slightly varied to compensate for variations in the placing of the other parts. Comparing the position of the parts shown in Fig. 2 with the position shown in Fig. 4, it must be evident that as the press opens and closes, the casing 60 will oscillate about the axis of the stud 59, and gear 50, and consequently the gear 62 will swing back and forth in a partial revolution about the gear 50. Now, assuming that the press gear 7 is driven in the direction indicated by the arrow thereon, (Figs. 2 and 4), the gear 50 will be driven in the direction of the arrow thereon, (Figs. 2 and 4). It will now be evident that when the gear 62 is swung upwardly from the position shown in Fig. 2 to the position shown in Fig. 4, it is being revolved in the same direction as the direction of rotation of the gear 50. On the other hand, when the press is open, the gear 62 will be swung from the position shown in Fig. 4 to the position shown in Fig. 2, and the direction in which it is thus revolved is contrary to the direction of rotation of the gear 50. As a consequence, the speed of rotation of the gear 62 will be diminished during the closing movement of the press and accelerated during the opening movement. Since the gear 66 is driven through the gear 64 by the gear 62, it must be evident that this rotative movement of the gear 66 will be uneven,—that is to say, during a portion of its rotation, its movement will be slow, and during the remainder of a given rotation, its movement will be relatively rapid.

In the cycle of the press, opening movement takes place in approximately one-half the rotation of the gear 7, and the closing movement also takes place in the remaining half of the rotative movement, while it is found that the gear 66 rotates approximately two-thirds of a rotation during the opening movement of the press, and one-third of the rotation on the closing movement, due to the described swinging movement of the pinion 62 with relation to the gear 50. This irregular rotative movement may be translated into a uniform reciprocatory movement, or a reciprocatory movement having any desired dwells, retardations or accelerations, by the use of a variation of the well-known Whitworth quick return motion, which will be hereinafter 120 125 130

described in connection with the second gripper mechanism.

First gripper mechanism—(See Figs. 8, 9, 10 and 11.)

5 Mounted in suitable bearings in the side frame members 68 and 69, is a rock-shaft 73 carrying sheet grippers, which it will be convenient to refer to as the first set of grippers, 10 since they act upon the sheet first by taking the same from the feed-table and delivering it to a second set of grippers. Loosely mounted on the rock-shaft 73, but held against swinging movement thereon, 15 is a lever, or a plurality of levers, 74 (herein two levers), which carry the grippers. Since these two levers and the parts carried thereby are exactly similar, a detailed description of one will suffice for both. Each 20 lever 74 is preferably forked, and provided with two arms 75—75, having formed thereon, or secured thereto, fixed grippers 76—76, having sheet-gripping surfaces 77—77 and shoulders 78—78, which may 25 serve as abutments for the front edge of the sheet. Supported upon the arms 75 are two movable grippers 79—79, herein pivoted at 30 80 to a forked yoke 81, the latter being secured to a rod 82 mounted to slide in a sleeve 83. This sleeve is provided with a longitudinal slot 84, in which a pin 85, secured to the rod 82, plays. Encircling the rod 82 is a spring 86, interposed between the yoke 81 and the sleeve 83, and tending to 35 move them apart, or in other words, tending to urge the grippers 79 toward the grippers 76. The sleeve 83 is formed to receive one arm of a lever 87, to which it is pivoted at 40 88. This lever is interposed between a pair of arms 89 on the lever 74, and is secured to a rock-shaft 90 by a key 91, located in a key-way, or spline, 92. The rock-shaft 45 90 is mounted in suitable bearings in the arms 89 of the lever 74, and is also journaled in bearings provided in one or more arms 93 secured to the rock-shaft 73. Therefore, the levers 74 may be adjusted longitudinally of the rock-shafts 90 and 73, and yet receive their rocking motion from the 50 shaft 73 without being actually secured thereto. The lever 74 and the lever 87 may be held against longitudinal sliding movement by providing the lever 87 with a split ear 87' and a clamping screw 87', by means 55 of which the lever 87 may be clamped to the rock-shaft 90. The yoke 81, carrying the grippers 79, may be held against lateral displacement by a link 94, pivoted at one end to the yoke 81, and at its other end to the lever 75. The movable gripper 79 is provided with a sheet-engaging surface 95, which co-operates with the sheet-engaging surface 77 of the fixed gripper 76, and said sheet-engaging surfaces preferably diverge

at their entrance, so as to guide the entering 65 edge of the sheet therebetween.

As a means for applying spring pressure to the grippers 79 at appropriate times in the operation of the machine, the rock-shaft 90 has secured thereto an arm 96, to which 70 is pivoted a rod 97 encircled by a spring 98, bearing at one end against a fixed collar 99 on the rod, and at its other end against a pivoted block 100, through which said rod is arranged to slide. A nut 101 and check-nut 102, threaded onto the rod 97, serve to limit the motion of the latter, under the influence of the spring 98. The arm 96 is fixed upon the rock-shaft 90 in such a position that in one position of the arm (see 80 full line position, Fig. 9), the arm is nearly in line with the rod 97, and consequently the spring 98 exerts its minimum force upon the springs 86 to cause the latter to urge the grippers 79 toward the grippers 76, the consequence being that at that time, the springs 86 furnish a very light pressure upon the sheet. When, however, the lever 75 is swung from the full line position (Fig. 9) to the dotted line position, the arm 96 is disposed 90 at a substantial angle (see dotted line position, Fig. 9) to the rod 97, the result being that the spring 98 will serve to apply additional pressure to the grippers by causing the pins 85 to seat, or bottom, in the ends 95 of the slots 84, thereby causing the pressure of the spring 98 to act through positive connections upon the grippers, without intervention of the springs 86, this occurring during the carrying movement of the grippers. 100

Since the pivot connecting the arm 96 to the rod 97 is placed eccentrically with relation to the axis of the rock-shaft 73, about which it swings, said pivot in swinging downward, will approach the abutment 100, and consequently cause the spring 98 to be placed under greater tension during the carrying movement of the grippers. Sometimes in operating on very thin cardboard, it is found desirable to utilize only the pressure of the springs 86, during the transferring of the sheet. Under such circumstances, the nut 101 and check-nut 102 may be adjusted to limit the motion of the rod 97, under the influence of the spring 98, so that 110 the spring 98 becomes practically ineffective. By utilizing the spring 86, pressure may be independently applied to the two pairs of grippers, and the two pairs may be caused to grip the sheet with substantially equal pressure. 115 120

A rocking motion may be imparted to the rock-shaft 73 and the described parts carried thereby by any suitable means, but herein, there is secured to the rock-shaft an arm 103, connected by a link 104 to a cam lever 105, fulcrumed on a stud 106, fixed to the side frame member 68, and said cam

125

lever having journaled thereon a cam roll 107, actuated by a suitable cam 108, the latter being herein formed in one face of the gear 66.

5 By the described mechanism, when the press closes, the grippers 76 and 79 are caused to swing forward into position to receive the sheet from the feed-table in a manner which will be more fully described 10 hereinafter, and at the proper moment, the grippers are positively opened by the engagement of a cam-roll 109 journaled on an arm 109' secured to the rock-shaft 90, with a cam 110 formed on or secured to the cam lever 32 hereinbefore described (see Figs. 4 and 5). This cam is so shaped and placed 15 that the grippers will open to receive the sheet from beneath the fingers 21, and when the press starts to open, the cam lever 32 will lift the cam 110, thus releasing the roll 109, and allowing the grippers instantly to 20 close under the combined pressure of the springs 86 and 98.

The grippers now having received the 25 sheet will be swung into the proper position to deliver the same to the second set of grippers, which will presently be described, and at the moment of delivery, the grippers will be partially relieved of the pressure of the 30 spring 98, so that the second set of grippers may draw the sheet from the first set against merely a slight resistance offered by the spring 98 acting through the springs 86 pressing the grippers upon the sheet. By 35 an inspection of Fig. 10, it will be seen that the two pairs of grippers on each lever 75 are so placed as to receive between them the grippers of the second set of grippers, which 40 will now be described.

40 *Second gripper mechanism*—(See Figs. 12 to 24, inclusive.)

Mounted in guideways 111 in the side frame member 68, and in guideways 112 in the side frame member 69, are two slides 113 and 114, rigidly connected to each other by rods 115 and 116. Preferably, the slide 113 is provided with shoulders 117 arranged in sliding contact with a finished face 118 of the side frame member 68, to hold the slide against lateral movement in one direction, while the slide is provided with a groove 119, which receives a key 120 secured to the frame member 68, to hold the slide against lateral movement in an opposite direction. At the other side of the machine, the slide 114 is preferably without lateral guides, so that the side frame is free to come and go somewhat, without affecting the position of the 60 slides 113 and 114.

Since these slides are very short as compared with the width of the machine, it is desirable to provide some means for insuring their movement in unison, so that the 65 sheet will be held square during its forward

motion. To this end, there is journaled in the slides a shaft 121, having secured thereto a pair of pinions 122 and 123, meshing with racks 124 and 125, secured to the side frame members 68 and 69, respectively.

70 Mounted in the slides 113 and 114, is a rock-shaft 126, which is capable of longitudinal sliding movement for a purpose which will be explained in connection with the side register mechanism hereinafter described. Mounted upon the rock-shaft 126 and upon the fixed rod 116, is a plurality of gripper supports 127 (herein two). Each of these gripper supports is capable of sliding on the fixed rod 116, but is compelled to 80 move longitudinally with the sliding rock-shaft 126, by being forked to provide a pair of arms 128, between which is located an arm 129 secured to the rock-shaft 126. The gripper supports 127 are capable of adjustment, longitudinally of the rock-shaft 126, the latter for that purpose being provided with a spline, and the arm 129 being provided with a key 130, and a split ear 131, having a clamping screw 132.

90 Each of the gripper supports, with the mechanism mounted thereon, is exactly similar to the other, and a detailed description of one will suffice for both. Mounted on each gripper support 127 is a gripper 133, which is fixed in the operation of the machine, but capable of lengthwise adjustment, it being provided for this purpose with a dove-tailed groove 134, which receives a correspondingly dove-tailed guide 135 on the gripper support 127. As a means for adjusting the gripper longitudinally, it may be provided with a transverse slot 136, having therein the head of an eccentric stud 137, provided with a shank 138 swiveled in the gripper support 100 127. The eccentric stud may be provided with a slot 139, to receive a screw-driver by means of which it may be conveniently rotated to advance or retract the gripper. By advancing one or the other of the grippers 133, the sheets may be squared very 110 readily. The gripper may be secured in the desired position of adjustment by a clamping screw 140 passing through a longitudinal slot 141 provided in the gripper, said screw 115 being threaded into the gripper support 127.

The gripper 133 is provided at its forward end with laterally-extending sheet-gripping surfaces 142, preferably having a slight 120 downward incline toward their extremities to facilitate the entrance of the edge of the sheet.

Coöperating with these fixed gripping surfaces are two movable grippers 143, having sheet-engaging surfaces 144, preferably having a downward incline corresponding to the surfaces 142. These movable grippers are preferably mounted on a pivot 145 on the gripper support 127, and said grippers are connected to each other by a pin 146. A 130

bell-crank lever 147, secured to a rock-shaft 148 mounted in bearings in the gripper support 127, is provided with a forked arm 149, which receives the pin 146. The bell-crank lever is provided with a pair of arms 150, pivoted at 151 to a collar 152 interposed between said arms. The collar 152 is secured to a rod 153, arranged to slide through a sleeve 154 pivoted at 155 to the arm 129, the latter for that purpose being forked to straddle the sleeve 154. A spring 156, encircling the rod 153, bears at one end against the sleeve 154, and at its other end against a nut 157, threaded on the rod and serving as a means of adjustment for the spring. A lock-nut 158 may be provided to secure the nut 157 in the desired position of adjustment.

As a means for rocking the shaft 126 to actuate the movable grippers 143, said rock-shaft has secured thereto an arm 159, having journaled thereon a cam-roll 160, located in the cam path of a stationary cam 161 secured to the side frame member 69. By giving the cam path the proper shape, it may be caused to utilize the forward and backward movement of the slides 113 and 114, and the described mechanism carried thereby to open and close the grippers. To this end, the cam is provided with two straight portions 162 and 163, and two depressed portions 164 and 165, the latter being shallower than the former. When the slides 113 and 114 and the mechanism carried thereby are in their retracted position shown in Figs. 16 and 20, the grippers are open. When, however, the slides and mechanism carried thereby start to advance, the cam roll 164 rises into the straight elevated portion 162 of the cam path, thus acting through the arm 159, rock-shaft 126, arm 129, and sleeve 154, to place the spring 156 under tension, and apply the spring pressure to close the grippers 143 upon the sheet, thus gripping the latter firmly against the grippers 143. This occurs at an appropriate time in the operation of the machine, as will be described hereinafter. The depth of the depression 165 is only sufficient to cause the spring pressure of the grippers upon the sheet to diminish at that point, without being entirely removed, and hence there is no danger of the grippers dropping the sheet during their forward movement. In some cases, when box blanks are being cut, it is desirable to have the cut extend clear to the front edge of the sheet, and since the sheet is to be held in the press by the second set of grippers during the cutting and creasing operation, it is necessary to provide the gripper 133 with a notch 166, to permit the sheet to be cut clear up to its front edge without interference with the gripper.

I will now describe the preferred form 65 of mechanism by which the slide 113 and 114, and the second set of grippers carried thereby, are given their forward and backward movements. The slide 113 is provided with a laterally projecting stud 167, connected by a link 168 to one arm of a bell-crank lever 169, fulcrumed at 170 upon a lever 171, the latter being fulcrumed on the stud 106, hereinbefore described. The other 70 arm of the bell-crank lever 169 has journaled thereon a cam-roll 172, located in a cam path provided in a cam 173, which is fixed in the operation of the machine, but is adjustable about the axis of the stud 106, as will presently be described. 75

The lever 171 is provided with a slot 174, in which is located a crank-pin, or roller, 175, carried by the gear 66 hereinbefore described. This mechanism constitutes what is familiarly known as the "Whitworth 80 quick return motion", with this difference, that the present device is a reversal of the Whitworth quick return motion. In other words, instead of converting a uniform rotary motion into a reciprocatory motion 85 having a slow motion in one direction and a quick return, it converts, or more correctly speaking, is capable of converting the non-uniform rotation of the gear 66 into a uniform, reciprocatory motion. This would be 90 the case if the slot 174 in the quick return lever 171 were made straight, but as it is desirable to give the second set of grippers a motion that will be more rapid at some points than at others, and which will have 95 suitable dwells, the slot 174 is given an irregular outline. This irregular shape of the slot and the results accomplished thereby, will be referred to more particularly 100 hereinafter. 105

The cam path of the cam 173 is formed in part on an arc of a circle struck from the axis on which the lever 171 rocks, while the remainder of the cam path takes a drop toward the fulcrum of the lever. It will be 110 convenient to refer to the first part of the cam path as the concentric part, and the remaining part as the dip, or drop. The extent of the concentric portion of the cam path is such that when the cam is placed 115 in the position shown in Figs. 12, 21 and 22, the cam-roll 172 will remain in the concentric part of the cam path during the entire stroke of the lever 171, and consequently the motion which is imparted to the second set of grippers will be uninfluenced by the cam 173. This is the extreme travel given to the second set of grippers, and consequently at this time, these grippers will move to their maximum distance beyond the front edge of the platen. This length of stroke is used for the smallest 120 size of sheet, since it is desirable that the 125

sheet shall be placed as near as possible to the center of the platen, so that the platen pressure may be equalized.

On the other hand, if it be desired to shorten the stroke of the second set of grippers, this may be accomplished by suitable adjustment of the cam 173, so that the stroke of the cam-roll 172 will begin at some point toward the left (Figs. 23 and 24) of the right-hand end of the cam path, and end at some point in the dip or drop in the cam path. As a result, the stroke of the second set of grippers will be shortened, the amount depending upon the position at which the cam 173 is set.

While any other suitable adjusting means may be employed, and while the adjusting means may be altogether dispensed with if desired, I preferably employ manually operable adjusting means, which will now be described. Referring particularly to Figs. 12, 13 and 33, the cam 173, as before stated, is pivotally mounted upon the stud 106. Formed on, or secured to the cam 173, is a segmental gear 174, with which meshes a pinion 177, secured to a shaft 178, the latter being journaled in a bracket 179 secured to the side frame member 68. The shaft 178 extends through a segmental slot 180, provided in the cam 173, and preferably through an index 181 co-operating with a series of suitable graduations 182 on the cam 173. These graduations and index may serve to assist the operator in properly adjusting the cam for the desired length of stroke of the second set of grippers.

The shaft 178 may, if desired, be provided with a clamping nut 183, which serves not only to firmly clamp the cam in the desired position of adjustment, but also serves as a means for tying the cam firmly to the bracket 179, the latter in turn being firmly fixed to the side frame 68, the consequence being that these parts provide, as it were, a sort of rigid, box-like structure for the mechanism supported thereby (see Fig. 32). Secured to the shaft 178, is a worm gear 184, meshing with a worm 185, the latter being formed on, or suitably secured to, a worm shaft 186, journaled in suitable bearings provided in the bracket 179. The worm shaft 186 may be provided at one end with a suitable collar, or shoulder 187, to take the end thrust of the shaft in one direction, and may be provided at its other end with a suitable collar, or shoulder 188, to take the end thrust in the opposite direction. If desired, the collar 187 may be in the form of a polygonal head, to receive a wrench, and the collar 188 may be knurled to facilitate manual rotation of the worm shaft.

By loosening the clamping nut 183, and rotating the worm shaft 186 in the proper

direction, the cam 173 may be adjusted to 65 the desired position, and secured in the selected position of adjustment, by tightening up the clamping nut 183.

Referring now to Figs. 21 and 22, wherein the cam 173 is shown in such a position of adjustment that the shaft 178 is located at the extreme right-hand end of the slot 180, this adjustment of the cam is such that with each rotation of the gear 66 carrying the crank-pin, or roll 175, the second set of grippers will be caused to travel its full stroke, since the cam-roll 172 does not leave the concentric portion of the cam path in the cam 173. Referring now to Figs. 23 and 24, wherein the cam 173 is shown in such a 80 position of adjustment that the shaft 178 occupies a position at the extreme left-hand end of the slot 180:—In this position of adjustment of the cam, the cam-roll 172 begins its stroke at the point shown in Fig. 23, 85 and ends its stroke at the point shown in Fig. 24. Now it must be evident that, although the fulcrum of the bell-crank lever 169 always travels to and fro a fixed distance, the distance through which the second set of grippers will travel will be dependent upon the control which the cam 173 exercises upon the cam-roll 172. That is to say, if when the cam-roll 172 in traveling toward the left (Fig. 23) reaches the end of 95 the concentric portion of the cam track, it starts to descend into the drop, or dip, the bell-crank lever 169 will commence to rock about its fulcrum in a clockwise direction with respect to the lever 171, by which it is 100 carried, and consequently, although the fulcrum of the bell-crank lever is still advancing toward the position shown in Fig. 24, there will be a slowing down in the movement of the link 168, and hence a lessening 105 of the stroke of the second set of grippers. To state a concrete example,—with the cam 173 placed in the position shown in Figs. 21 and 22, the second set of grippers may have a stroke of twelve inches, and will 110 travel its maximum distance into the press, but with the cam placed in the position shown in Figs. 23 and 24, the stroke of the grippers may be reduced to only nine inches, and the grippers will travel into the press 115 their minimum distance. By properly adjusting the cam, any desired variation in stroke between these may be obtained.

Referring now to the slot 174 in the lever 171, it has already been stated that this slot 120 may be given such a shape as to cause the grippers to be given a motion which may have suitable dwells, or pauses, and may be slow or fast according to the requirements 125 of the grippers. Now, it must be evident that since the second set of grippers is to hold the sheet stationary in the press during the impression, the grippers must pause

in their motion, and to that end, the slot 174 is formed with a portion 189, which in the position of the lever 171 shown in Fig. 22, is concentric or coincident with the path of the crank-pin or roll 175. The extent of this concentric portion 189 of the slot in the lever is, of course, determined by the length of the dwell required.

When the sheet has been cut and creased, and the press opens, it is desirable that the second set of grippers shall carry the sheet as rapidly as possible out of the press, transfer the sheet to the third set of grippers, and then recede to its initial position, where it is to receive a new sheet from the first set of grippers. To this end, the slot 174 is provided with an abrupt turn 190, which will produce the desired movement (see Fig. 25), and when the second set of grippers has reached the end of its stroke, the new sheet is transferred thereto from the first set of grippers. The sheet now, having been transferred from the first set of grippers to the second set, is carried forward into the press.

It will be readily apparent that when the press is closing and the slides 113 and 114, together with the second set of grippers and all the other mechanism carried by said slides, are advancing downwardly to carry the sheet into the press, these parts will acquire considerable momentum, and therefore, in order to counterbalance the weight of these parts and take up any back-lash which might result in an inaccurate positioning of the sheet, I provide suitable means, herein a torsional spring 191, encircling the shaft 121, said spring having one end fixed to a collar 192 secured to said shaft, and its other end fixed to an abutment 193, through which the shaft passes, this abutment being fixed to the rods 115 and 116. When the gripper mechanism advances downwardly to carry the sheet into the press, the spring 191 will be wound and placed under such tension that it will take up all of the back-lash of the parts, and moreover, when the grippers start to rise, the power stored up in the spring will assist the driving mechanism to lift the gripper mechanism. In fact, it is found that the power thus stored up is practically sufficient in itself to return the parts to their initial position.

55 Side register mechanism—(See Figs. 26 to 31, inclusive.)

If desired, there may be provided a side register mechanism, which when the second set of grippers has received the sheet, will cause the sheet and grippers to be shifted bodily, so as to accurately register sidewise. To that end, the rock-shaft 126, which carries the supports of the second set of grippers, may be mounted to move longitudi-

nally, and there may be provided suitable means actuated by contact with the edge of the sheet to determine the extent of such movement. Herein, longitudinal motion is imparted to the shaft 126 by a cam-roll 194, journaled thereon and engaging a fixed cam 195, which is herein for convenience of manufacture formed on the cam 161, secured to the side frame member 69. This cam-roll is urged toward its cam by a spring 196 (see Fig. 1), bearing at one end against the fixed abutment 193, and at its other end against a collar 197, secured to said shaft. It will now be evident that if the spring 196 were to hold the cam-roll 194 continuously in contact with the cam 195, as the second set of grippers is moved forward and back, it would be shifted laterally a distance equal to the throw of the cam.

I will now describe the means by which the lateral motion of the sheet and the second set of grippers is stopped, when the side edge of the sheet has reached a predetermined point. Formed on the sliding rock-shaft 126, is a rack 198, which (see Fig. 27) is given a circular formation because of the rocking motion of said shaft. This rack meshes with a pinion 199, secured to a sleeve 200, the latter having fixed thereto a ratchet 201. The sleeve 200 is journaled on a stud 202, fixed to a support 203. This support is mounted upon the fixed rods 115 and 116, in such a manner as to be capable of longitudinal adjustment thereon, and is held fixed in the desired position of adjustment by suitable means, herein a clamping stud 204 and nut 205, said stud having a lateral recess 206, which receives the rod 116.

Cooperating with the ratchet 201 is a pawl 207, pivoted on a stud 208 and urged toward said ratchet by a spring 209. Carried by the pawl 207 is a dog 210, having a tooth 211 cooperating with a rack-bar 212 provided with one or more teeth 213, each of which is provided at its forward side with an abrupt shoulder 214, and at its rearward side with an inclined surface 215, for a purpose which will presently appear. The rack-bar 212 is mounted to slide in a suitable guide 216, and is limited in its movement by a fixed pin 217, located in a slot 218 provided in said rack-bar. A spring 219, secured at one end to a fixed pin 220 and at its other end to a pin 221 carried by the rack-bar 212, tends to hold the rack-bar in the position shown in Fig. 26. The rack-bar 212 is connected to a trigger 222 pivoted at 223 upon a supporting plate 224. The trigger 222 is connected to the rack-bar 212 preferably by being provided with a tooth 225 located in the slot 226 provided in said rack-bar. The trigger 222 is provided with a suitable sheet edge engaging surface 227, adapted to be engaged by one side edge

of the sheet, when the latter is shifted laterally, while grasped by the second set of grippers. When this engagement occurs, the rack-bar 212 will be shifted longitudinally in the direction of the arrow thereon (Fig. 31), whereupon the particular tooth 213, which is engaged by the tooth 211 of the dog 210, will allow the latter to release the pawl 207, and permit the same to engage the ratchet 201 and lock the same against further rotation under the influence of the pinion 199 and rack 198. It will now be evident that since the shaft 126 is locked against longitudinal sliding motion, the cam-roll 194 carried thereby will no longer follow its cam 195 under the influence of the spring 196, and consequently, the grippers carried by the shaft 126 will be held in the proper position to maintain an accurate side register of the sheet, when the latter is carried into the press.

As a means for resetting the described mechanism, so that the same shall be prepared to act upon the next sheet, I may provide suitable means actuated by the equalizing shaft 121 to withdraw the pawl 207 from its ratchet 201, and simultaneously withdraw the tooth 211 of the dog 210 from its position between the teeth 213 of the rack-bar 212. To this end, there is loosely mounted upon the stud 208 a sleeve 228, having formed on, or secured thereto, an arm 229 provided with a pin 230 adapted to engage the pawl 207 in the end of a slot 231 provided in the latter. Formed on, or secured to the sleeve 228, is a worm gear segment 232, meshing with a worm 233 on the shaft 121. When, during the backward movement of the second set of grippers, the shaft 121 is rotated by the coöperating action of the pinions 122 and 123 with the racks 124 and 125, the worm 233 acts through the worm gear segment 232, arm 229 and pin 230 to withdraw the pawl and dog from their described engagement, and thus allow the trigger 222 and rack-bar 212 to be returned to their initial position under the influence of the spring 219. Contemporaneously, the shaft 126, rack 198, pinion 199, and ratchet 201, are returned to their initial position under the influence of the cam 195. In order that the side register mechanism may be adjusted laterally upon the fixed rods 115 and 116, the worm 233 is provided with a key 234, arranged to slide in a keyway or spline 235, provided in the equalizing shaft 121, and the worm is held in its proper position with respect to the worm gear segment 232, by being placed between two cross members 236 and 237 of the adjustable sliding support 203.

It quite often happens that the sheets are cut out of square, that is to say, the side edges of the sheet are not exactly at right angles with the front edge. In many cases,

the box blanks, before being creased and cut, are printed upon a press similar in its general characteristics to the cutting and creasing press, and during the printing operation, one of the side edges of the sheet is placed against a side gage, which insures the proper side register of the sheet. Now it must be evident that, if the side edge of the sheet is out of square, the trigger 222 should engage the edge of the sheet at the same point where the side register gage of the printing press engaged the sheet during the printing of the latter. Otherwise, the sheet would not be accurately side-registered for the cutting and creasing operation. To this end, therefore, the trigger 222, and the rack-bar 212 are adjustable longitudinally of the side edge of the sheet, this being accomplished by adjustably mounting the supporting plate 224 upon the supporting member 203. Herein, the member 203 is provided with guideways 238, in which a tongue 239 on the plate 224 is mounted to slide. The plate 224 may be held in a plurality of predetermined positions of adjustment corresponding to the spacing of the teeth 213 of the rack-bar 212. Herein, this is accomplished by providing the adjustable plate 224 with a tooth, or a pair of teeth, 240, interlocking with two adjacent teeth of a series of teeth 241, formed on the guideways 238. The plate 224 may be adjusted by simply lifting the same slightly and moving it along the required distance, after which the teeth 240 are dropped into place. The plate may then be secured by suitable means, herein a bolt 242, passing through a slot 243 provided in the member 203, and having a nut 244 (see Figs. 28 and 30), by means of which the plate is borne down firmly against its guideways. The teeth 240 and 241 are utilized in order that the teeth upon the rack-bar, as hereinbefore described, will always be properly placed, so as to coöperate with the tooth 211 of the dog 210.

Since the side edge of the sheet must be supported so as to coöperate with the trigger 222, and moreover, since the trigger and its supporting plate 224 must be made very long and thin, in order to extend between the platen and bed of the press, when the latter is closed, it is desirable that there shall be provided a slide 245, which herein is bolted to the inside of the supporting member 203, said slide being mounted to slide in a suitable fixed guide 246. Herein, the guide 246 is in the form of a channel (see Fig. 29), provided with finished webs 247, forming guideways for the slide 245, the latter for this purpose being provided with finished grooves 248, to receive the same. Herein the guide 246 is provided with a jaw 249, in which is placed a collar 250, encircling the stay-rod 70, hereinbefore described. This holds the guide 246 against

forward and backward movement, while at the same time permitting the same to be adjusted laterally with the other parts of the side register mechanism.

- 5 As before stated, it is necessary to provide suitable means to support the edge of the sheet, so that it shall properly engage the trigger 222. For this purpose, there is secured to the guide 246 a sheet-supporting plate 251, which serves to support the edge of the sheet, as well as to form a supporting guide for the plate 224. This supporting plate 251 is located beneath the trigger 222, when the trigger is retracted 10 (see Figs. 26 and 27), but when the sheet is carried into the press, the trigger and the plate 224 advance along the supporting plate 251 until the trigger occupies a position well in advance of the supporting plate 251. 15 The latter plate, as will be evident from an inspection of Fig. 1, is placed close to the edge of the platen 16, when the latter is open, so that inasmuch as there is only a slight gap separating the supporting plate 25 and the platen, the side register trigger and the plate 224, on which it is pivoted, are accurately supported and guided onto the face of the platen. 20

30 *Third gripper mechanism*—(See Figs. 1 to 20, and 32 to 37, inclusive.)

Mounted to slide in suitable ways 252 and 253 in the side frame members 68 and 69, respectively, are two slides 254 and 255, connected to each other by a fixed rod 256 and rock-shaft 257, on which one or more gripper supports 258 may be mounted. These gripper supports (herein two), together with the parts supported thereby, are preferably 40 exactly similar, and hence a detailed description of one will suffice for both.

Referring now more particularly to Figs. 34, 35 and 36, the gripper support 258 is provided with a pair of arms 259, having 45 suitably formed thereon, or secured thereto, fixed grippers 260. Mounted in bearings in the arms 259 is a rock-shaft 261, on which is fixed a pair of grippers 262. The fixed grippers 260 are provided with sheet-engaging surfaces 263, and the rocking grippers 262 are provided with sheet-engaging surfaces 264, the latter being herein formed eccentrically with relation to the axis of the rock-shaft 261, so that when once the sheet 55 is introduced between the grippers, any effort to withdraw the same will only result in the sheet being gripped all the more firmly. Preferably, the sheet-engaging surfaces 263 and 264 diverge quite sharply at 60 their entrance, so as to guide the sheet with certainty and accuracy into the proper position to be gripped therebetween.

The pressure for the movable grippers may be supplied by a spring 265, encircling 65 the rod 266, bearing at one end against a

fixed abutment 267, and at its other end against a shoulder 268 on said rod, the latter being pivoted at 269 to one of the rocking grippers 262. The rod 266 is mounted to slide through a washer 270, and through the forked abutment 267, against which the washer rests. The other end of the rod 266 is herein provided with a slot 271, in which is located a pin 272 secured to a lever 273, mounted on the rock-shaft 257. The slot 271 provides a certain amount of lost motion between the rod 266 and the lever 273, so that during the gripping action, the pressure of the spring 265 may be exerted without restraint. In order that the grippers may be 80 capable of lateral adjustment, while at the same time providing a construction whereby the lever 273 may be secured to the rock-shaft 257, the support 258 is provided with a fork 274, between the sides of which the 85 lever is interposed, and the latter is provided with a key 275, located in a key-way, or spline, 276, provided in the rock-shaft 257. The support 258 and the parts carried thereby may be held against longitudinal sliding movement on the rod 256 and rock-shaft 257, by providing the lever 273 with a split ear 277, and a clamping screw 278, by means of which the lever may be caused to grip the rock-shaft. 95

As a means for holding the grippers open to receive the sheet, there is herein provided a collar 279, secured to the gripper rock-shaft 261, said collar being provided with a tooth 280, normally engaged by a trigger, or latch, 281, secured to a rock-shaft 282 mounted in the arms 259. This trigger, or latch, extends across the opening between the grippers (see Fig. 35) in position to be engaged by the edge of the entering sheet, 105 whereby the trigger or latch is tripped, and the grippers 262 released so as to grip the sheet under the influence of the spring 265. The trigger or latch 281 may be normally held in locking engagement with the tooth 280 by a suitable spring, herein in the form of a helical torsional spring 283, encircling the rock-shaft 282, and having one end secured to said rock-shaft, and the other to the adjacent arm 259. 110

It will be evident that the grippers, after receiving the sheet from the second set of grippers, and having carried the sheet to a point above the receiving rack, or elevator, must be provided with some means for releasing the sheet and resetting the movable grippers and trigger, ready to receive another sheet. To that end, there is secured to the rock-shaft 257 a cam-lever 284, on which is journaled a cam-roll 285, adapted to co-operate with the fixed cam 286 secured to the stay-rod 71 (see Figs. 1 and 36). The cam-roll may be maintained in operative engagement with the cam by a spring 287, encircling a rod 288 pivoted at 289 to the cam 120 125 130

lever. This spring bears at one end against a shoulder 290 on the rod 288, and at its other end against a fixed abutment 291, in the form of a lug provided on a collar 292, secured to the rod 256. When the cam-roll 285 passes entirely off of the cam 286, as it does during the forward motion of the grippers, there must be provided a suitable stop to prevent the cam-roll from dropping below the forward extremity of the cam, and to that end, the rod 288 is herein provided with a nut 293, and a check-nut 294, threaded thereonto, and arranged to engage the lug 291, through which the rod slides.

15 It will now be evident that when the grippers return, after having received the sheet from the second set of grippers, the cam-roll 285 will ride up onto the cam 286, and will act through the lever 284, rock-shaft 257, lever 273 and rod 266, to positively swing the grippers 262 into open position, so as to release the sheet. As a means for positively ejecting the sheet from the grippers, when thus released, there may be provided an ejector 295, herein in the form of a plate secured to a rod 296, mounted to slide in a guide 297, said rod being pivoted at 298 to a lever 299, the latter being fulcrumed at 300, on the support 258. The lever 299 is herein connected by a lever 301 to the lever 273. It will now be apparent that when the lever 273 is rocked in the direction of the arrow thereon (Fig. 35), it will act through the described connections to cause the grippers to release the sheet and the ejector to eject the sheet from between the grippers.

10 The slides 254 and 255 may be actuated by any suitable mechanism to impart a forward and backward motion thereto, but I preferably employ the mechanism which I will now describe. Formed on, or secured to, the slides 254 and 255, are rigid arms 302 and 303, connected by links 304 and 305 to special links 306 and 307 of a pair of chains 308 and 309. These chains are supported and carried at one end by sprocket wheels 310 and 311, and at the other by sprocket wheels 312 and 313. Herein the sprocket wheels 312 and 313 are idlers, and are mounted on studs 314 and 315, in slots 316 and 317, and are provided with suitable means of adjustment, herein a pair of adjusting screws 318 and 319, preferably provided with locknuts 320 and 321.

15 The other sprocket wheels 310 and 311 are secured, respectively, to spur gears 322 and 323, provided respectively with hubs 324 and 325, journaled in the side frames 68 and 69, respectively. These spur gears mesh with, and are driven by, gears 326 and 327, secured to a shaft 328 and having their hubs journaled in the side frame members 68 and 69. The hub 324 passes through the side frame 68, and has secured to its outer end

a spur gear 329. This gear meshes with, and is driven by, a gear 330, suitably formed on, or secured to, a gear 331 journaled on a stud 332, the latter being secured to the side frame 68. The gear 331 in turn meshes with, and is driven by, the gear 66 hereinbefore described.

20 By means of the gearing just described, the chains 308 and 309 are driven in the direction of the arrows thereon (Figs. 20 and 32), and the chains moving continuously in one direction act to impart to the slides 254 and 255 a reciprocatory motion, through the use of the links 304 and 305. Referring now to the motion of the gear 66, it will be remembered that this gear has an uneven rotation, and is rotated approximately two-thirds of a rotation on the opening movement of the press, and approximately one-third of a rotation on the closing movement of the press. This variable movement will consequently be imparted through the gearing just described to the chains 308 and 309, and consequently, the slides 254 and 255, and the gripper mechanism carried thereby, will receive a relatively slow movement during the closing of the press, and a relatively rapid movement during the opening of the press. The rapid movement of the grippers during the opening of the press is desirable, owing to the fact that it is toward the end of this movement that the third set of grippers deposits the sheet upon the pile in the receiving rack, or elevator. In Fig. 20, the parts are shown in the position which they occupy when the press is fully opened. As a means for preventing the links 304 and 305 from vibrating while the special chain links 306 and 307 are traveling from left to right (Fig. 20), the arms 302 and 303 are herein provided with lugs 333 and 334, which (see Figs. 20 and 32) are adapted to limit the swinging motion of the links 304 and 305.

General operation.

110

Having thus specifically described the machine and the mode of operation of its various mechanisms, I will now describe the general operation, and the co-operative action of its various mechanisms, referring more particularly to Figs. 38, 39 and 40. The operator places a sheet A upon the feed-table, with its front edge against the abutments 22 of the fingers 21, and with one side edge against the stop 20 (Fig. 1). When the press closes, the first set of grippers advances and grasps the front edge of the sheet (Fig. 38). At this moment, the fingers 21 are lifted, thus releasing the sheet to allow the latter to be drawn off the feed-table. In the meantime, a previously fed sheet B is being held in the press by the second set of grippers (Fig. 38), while the sheet is being cut and creased.

Referring now to Fig. 39, which shows the press about one-quarter open, the first set of grippers, having grasped the sheet A, starts to swing, and carry the same toward the point where it is to be transferred to the second set of grippers. Meantime, the third set of grippers has advanced to a point near the edge of the platen, and the second set of grippers has retracted, 5 carrying the sheet B into the third set of grippers (see Fig. 39). The third set of grippers is already open, ready to receive the sheet B, while the tension of the springs 153 of the second set of grippers is diminished at this moment, under the influence of the depressed portion 165 of the cam 161. The front edge of the sheet B strikes and trips the triggers 281, whereupon the third set of grippers firmly grasps the sheet 15 and, since at this moment the second set of grippers is retracting more rapidly than the third set, the sheet will be withdrawn from the second set. The second set of grippers, now being empty, continues to move 20 upwardly toward the right (Fig. 39), and the third set of grippers moves rapidly upward toward the right, carrying the sheet B off the face of the platen, to a point above a suitable feed rack indicated in dotted lines 25 (Fig. 40), and releases the sheet, allowing the same to fall upon a pile in the rack.

Referring now to Fig. 40, the second set of grippers, having reached the limit of its travel toward the right, opens to receive the sheet A, while the first set of grippers carries the front edge of the sheet into the second set, and brings the front edge of the sheet up against the shoulders of the second set. At this moment, there is a minimum tension 30 upon the grippers of the first set, owing to the fact that the pressure of the spring 98 is at this moment diminished (Fig. 9). The platen is now fully open, and starts to close. Now, as the grippers of the second set start 35 toward the platen and close upon the sheet, the latter will be pushed from between the grippers of the first set between which the sheet is held, by merely a light spring pressure.

50 It will be observed that (see Fig. 40), while the sheet A is being transferred from the first set of grippers to the second set, about half of the sheet is lying practically flat upon the face of the platen, onto which 55 it has been drawn by the first set of grippers. In transferring the sheet from the first set of grippers to the second set, the shoulders of the first set travel a short distance beyond the shoulders of the second set 60 (see Fig. 41), thus bringing the front edge of the sheet up against the shoulders of the second set. The grippers of the second set now start toward the platen, but do not close until after they have started, and hence 65 if the sheet should by any possibility be

askew, or not up against the shoulders of both pairs of grippers, of the second set, the front edge of the sheet will engage first one shoulder and then the other and will at once be brought with certainty into accurate register against both shoulders before the grippers have fully closed and before the sheet has been entirely withdrawn from the first set of grippers.

The side register mechanism now comes 70 into play, and automatically shifts the sheet laterally to whatever extent may be necessary to properly position the same laterally, it being understood that the sheet is meanwhile grasped by the second set of grippers, 80 which is, of course, moved bodily with the sheet. The second set of grippers continues its advance, and carries the sheet into position upon the platen, firmly holding the sheet accurately positioned in both directions, ready for the cutting and creasing operation. The press closes, performs the cutting and creasing operation, and then opens after which the second set of grippers recedes, carrying the sheet out of the 90 press in the manner described in connection with sheet B, after which the finished sheet is transferred to the third set of grippers, and finally deposited upon the receiving rack, or elevator.

95 While I have herein shown and described one specific embodiment of my invention for illustrative purposes, and have disposed and discussed in detail the construction and arrangement incidental to one 100 specific application thereof, it is to be understood that the invention is limited neither to the mere details or relative arrangement of parts, nor to its specific embodiment herein shown, but that extensive 105 deviations from the illustrated form or embodiment of the invention may be made without departing from the principles thereof.

Having thus described one embodiment of 110 my invention, what I claim and desire by Letters Patent to procure is:—

1. The combination with two coöperating press members, of two sets of opening and closing sheet grasping devices, both sets 115 having abutments arranged for engagement with the edge of the sheet to position the latter, each set being distinct from and movable relatively to said press members, and means relatively to actuate said sets of devices to cause one to bring the sheet up against the abutment of the other and to cause said other to grasp the sheet and said one to withdraw from the sheet leaving the latter in the grasp of said other.

120 2. The combination with a press having a movable press-member, of two sets of gripping means carried by said press-member, and instrumentalities to relatively actuate said sets of gripping means to cause 125

130

one to take a sheet and transfer it directly to the second, and the second to carry the sheet into and out of the press.

3. The combination with a pair of cooperating press members, of three pairs of opening and closing grasping means, each pair being distinct from and movable relatively to said press members, and instrumentalities relatively to actuate said sets of gripping means to cause one to take a sheet and transfer it to the second, and the second to carry the sheet in one direction into the press and in another direction out of the press and transfer it to the third set.
4. The combination with a press having a movable press-member, of three sets of gripping means carried by said press-member, and instrumentalities to relatively actuate said sets of gripping means to cause one to take a sheet and transfer it to the second, and the second to carry the sheet into and out of the press and transfer it to the third set.

5. The combination with a press having a movable press-member, an eccentric member, and a draw-bar connecting said eccentric member to said press-member; of sheet-feeding means carried by said press-member, and means for deriving the feeding movement of said sheet-feeding means directly from said eccentric member without the intervention of said press member.

6. The combination with a press having a movable press-member, a crank-pin, and a draw-bar connecting said crank-pin to said press-member; of sheet-feeding means carried by said press-member, and driving means including gearing connecting said sheet-feeding means to said crank-pin.

7. The combination with a press having a movable press-member, a crank-pin, and a draw-bar connecting said crank-pin to said press-member; of sheet-feeding means carried by said press-member, and driving means connecting said crank-pin to said sheet-feeding means, said driving means including a gear secured to said crank-pin, and a pinion meshing with said gear and carried by said draw-bar.

8. The combination with a press having a movable press-member, a crank-pin, and a draw-bar connecting said crank-pin to said press-member; of sheet-feeding means carried by said press-member, and driving means connecting said crank-pin to said sheet-feeding means, said driving means including a gear secured to said crank-pin, a shaft journaled in bearings carried by said draw-bar, a pinion secured to said shaft and meshing with said gear, a second pinion secured to said shaft, and a gear meshing with said second pinion.

9. The combination with a press having a swinging press-member, a crank-pin, and a draw-bar connecting said crank-pin to said

press-member; of sheet-feeding means carried by said press-member, and driving means connecting said crank-pin to said sheet-feeding means, said driving means including a lever provided with a slot, and a crank-pin located in said slot and having a relatively fast revolving motion during the opening movement of the platen and a relatively slow revolving motion during the closing movement of the platen.

10. The combination with a press having a swinging-press member, a crank-pin, and a draw-bar connecting said crank-pin to said press-member; of sheet feeding means including grippers carried by said press-member, and driving means connecting said crank-pin to said sheet-feeding means, said driving means including a driving gear concentric with the platen end of said draw-bar, a driven gear meshing with and driven by said driving gear, a support on which said driven gear is journaled, said support being mounted to rock about the axis of said driving gear during the opening and closing movement of said platen, a lever connected to said grippers and provided with a slot, and a crank-pin located in said slot and driven by said driven gear.

11. A sheet-feeding mechanism for presses having, in combination, sheet-gripping means including a pair of grippers having a main closing spring and an auxiliary closing spring, both acting on one of said grippers, means to impart a carrying movement to said sheet-gripping means, means to take a sheet from said sheet-gripping means and feed the sheet, and means automatically to render said auxiliary closing spring ineffective, while still maintaining the pressure of said main spring upon the sheet, while the sheet is being taken from said sheet-gripping means.

12. A sheet-feeding mechanism for presses having, in combination, sheet-gripping means having a light closing and a relatively heavier closing spring, means to impart a carrying movement to said sheet-gripping means, means to take a sheet from said sheet-gripping means and feed the sheet, and means automatically to render said heavier spring ineffective while the sheet is being taken from said sheet gripping means.

13. A sheet-feeding mechanism for presses having, in combination, sheet-gripping devices having closing pressure means, means to impart a carrying movement to said sheet-gripping devices, means to take a sheet from said sheet-gripping devices and feed the sheet, and means consequent upon said carrying movement to diminish but retain a part of the pressure exerted by said pressure means while the sheet is being taken from said sheet-gripping means.

14. A sheet-feeding mechanism for presses having, in combination sheet-gripping de-

5 vices having closing pressure means, means to impart a carrying movement to said sheet-gripping devices, means to take a sheet from said sheet-gripping devices and feed the sheet, and means consequent upon said carrying movement to diminish but retain a part of the pressure exerted by said pressure-means, while the sheet is being taken from said sheet-gripping means and altogether remove said pressure and open said sheet-gripping means after the sheet has been withdrawn therefrom.

ing said sliding means to cause the same to carry the sheet into and out of the press, and a spring connected to said pinion and tending to resist the advance of said sliding means.

26. The combination with a press having a press-member, of a pair of slides carried by said press-member, gripping means carried by said slides, a pair of racks fixed on 10 said press-member, a pair of pinions meshing with said racks, a shaft connecting said pinions to cause the same to rotate in unison, means for positively advancing and retracting said slides to cause said gripping means 15 to carry the sheet into and out of the press, and a spring connected to said shaft and arranged to be placed under tension by the rotation of said shaft during the advance of said slides.

20 27. A sheet-feeding mechanism for presses having, in combination, two sets of gripping means, instrumentalities to relatively actuate said gripping means to cause one to take a sheet and transfer it to the second, and the 25 second to carry the sheet positively into and out of the press, and means to vary the travel of the second set of gripping means.

28. A sheet-feeding mechanism for presses having, in combination, two sets of gripping 30 means, instrumentalities to relatively actuate said gripping means to cause one to take a sheet and transfer it to the second, and the second to carry the sheet positively into and out of the press, and means including an 35 adjustable cam to vary the travel of the second set of gripping means.

29. A sheet-feeding mechanism for presses having, in combination, two sets of gripping 40 means, means to actuate one set of gripping means to cause the same to transfer the sheet to the second gripping means, means to actuate the second gripping means to cause the same to carry the sheet positively into the 45 press, and manually adjustable means to vary the travel of the second set of gripping means into the press.

30. A sheet-feeding mechanism for presses having, in combination, two sets of gripping 50 means, means to actuate one set of gripping means to cause the same to transfer the sheet to the second gripping means, means including a fixed travel actuating device for imparting a to and fro motion to the second 55 set of gripping means to cause the same to carry the sheet positively into and out of the press, and adjustable means to vary the travel of the second set of gripping means into the press.

60 31. A sheet-feeding mechanism for presses having, in combination, sheet-gripping means, means including a fixed travel actuator for positively actuating said gripping means to cause the same to carry a sheet into 65 and out of the press, and adjustable means

to vary the distance to which the gripping means is moved by said actuator.

32. A sheet-feeding mechanism for presses having, in combination, sheet-gripping means, means including a floating lever for actuating said gripping means to cause the same to carry a sheet into and out of the press, and adjustable means to control the rocking motion of said lever thereby to vary the travel of said gripping means.

70 33. A sheet-feeding mechanism for presses having, in combination, sheet-gripping means, a lever connected to said gripping means, means to impart a to and fro movement to the fulcrum of said lever, and means connected to said lever to cause the same to rock upon its fulcrum during the to and fro movement of said fulcrum.

75 34. A sheet-feeding mechanism for presses having, in combination, sheet-gripping means, a lever connected to said gripping means, means to impart a to and fro movement to the fulcrum of said lever, and an adjustable cam co-operating with said lever to cause the same to rock upon its fulcrum during the to and fro movement of said fulcrum.

80 35. A sheet-feeding mechanism for presses having, in combination, sheet-gripping means, a lever connected to said gripping means, means to impart a to and fro movement to the fulcrum of said lever, and an adjustable cam co-operating with said lever, said cam having a path a portion of which is parallel to or coincident with the path of said fulcrum, and a portion of which is offset.

85 36. A sheet-feeding mechanism for presses having, in combination sheet-gripping means, a lever connected to said gripping means, means to move said lever bodily to and fro, thereby to move said sheet-gripping means, and adjustable means to cause said lever to swing during its said movement thereby to vary the travel of said sheet-gripping means.

90 37. A sheet-feeding mechanism for presses having, in combination, sheet-gripping means, a floating lever connected to said gripping means, a second lever upon which said floating lever is fulcrumed, means to oscillate said second lever, and means connected to said floating lever to rock the same upon its fulcrum during its movement under the influence of said second lever.

95 38. A sheet-feeding mechanism for presses having, in combination, sheet-gripping means, a floating lever having one arm connected to said gripping means, a second lever upon which said floating lever is fulcrumed, means to oscillate said second lever, 100 and a guide for the other arm of said floating lever, said guide having a path a portion of which is concentric with the fulcrum of said second lever and a portion of which is offset, said guide being mounted for ad- 105 110 115 120 125 130

justment about the fulcrum of said second lever.

39. A sheet-feeding mechanism for presses having, in combination, means to carry a sheet into and out of the press, sheet-gripping means to receive the sheet as it comes out of the press, means actuated by engagement with the entering sheet to cause said sheet-gripping means to grip the sheet, means to impart a carrying movement to said sheet-gripping means, and means consequent upon said carrying movement to cause said sheet-gripping means to grip the sheet with a force proportionate to the pull exerted thereon.

40. A sheet-feeding mechanism for presses having, in combination, sheet-gripping means, means actuated by contact with the entering sheet to cause said sheet-gripping means to grip the sheet, means to impart a carrying movement to said sheet-gripping means, and means carried by said sheet-gripping means to eject the sheet from said sheet gripping means.

41. A sheet-feeding mechanism for presses having, in combination, sheet-gripping means, holding means normally to hold said sheet-gripping means open to receive a sheet, means operated by engagement with the entering sheet to actuate said holding means to cause the same to allow the gripping means to close upon the sheet, means to impart a carrying movement to said sheet-gripping means, and means consequent upon said carrying movement to cause said gripping means to grip the sheet.

42. A sheet-feeding mechanism for presses having, in combination, sheet-gripping means including a gripper closing spring, means normally to hold said gripping means open against the tension of said spring, means operated by engagement with the entering sheet to actuate said holding means to allow said gripping means to close under the influence of said spring, means to impart a carrying movement to said gripping means, and means to utilize said carrying movement to cause said gripping means to grip the sheet.

43. A sheet-feeding mechanism for presses having, in combination, self-closing sheet-gripping means, means normally to hold said gripping means open, means operated by engagement with the entering sheet to actuate said holding means to allow said gripping means to grip the sheet, means to impart a carrying movement to said gripping means, means to utilize said carrying movement to cause said gripping means to grip the sheet, and means to open said gripping means.

44. A sheet-feeding mechanism for presses having, in combination, self-closing sheet-gripping means, means normally to hold

said gripping means open, means operated by engagement with the entering sheet to actuate said holding means to allow said gripping means to grip the sheet, means to impart a carrying movement to said gripping means, means to render said gripping means ineffective to grip the sheet, and means carried by said gripping means to eject the sheet therefrom.

45. A sheet-feeding mechanism for presses having, in combination, sheet-gripping means, means for imparting a reciprocatory movement thereto, including a chain, a link swingingly connected to said chain and to said sheet-gripping means, and means to limit the swinging motion of said link.

46. A sheet-feeding mechanism for presses having, in combination, sheet-gripping means, a pair of slides by which said sheet-gripping means is carried, a pair of chains, means for driving said chains in unison continuously in one direction, a pair of arms on said slides, respectively, a pair of links swingingly connected to said arms and to said chains, respectively, and means for limiting the swinging motion of said links relatively to said arms.

47. A sheet-feeding mechanism for presses having, in combination, two sets of gripping means each provided with gage stops for the edge of the sheet, and instrumentalities to relatively actuate said sets of gripping means to cause one to take a sheet and by slipping frictional engagement with the first set, push it up against the stops of the second, and the second to carry the sheet into and out of the press.

48. The combination with a press having a pair of press-members having flat coöperating surfaces, of two sets of opening and closing sheet grasping means, and instrumentalities to relatively actuate said sets of opening and closing sheet grasping means, means to cause one to take a sheet and transfer it to the second and the second to carry the sheet in a plane parallel to one of said surfaces into and out of the press.

49. A sheet-feeding mechanism having, in combination, three sets of gripping means two of which are provided with gage stops for the edge of the sheet, and instrumentalities to relatively actuate said sets of gripping means to cause one having gage stops to take a sheet and transfer it to the second having gage stops, and the second to carry the sheet into and out of the press and transfer it to the third set.

50. The combination with a press having a pair of press members having flat coöperating surfaces, of three sets of gripping means, and instrumentalities to relatively actuate said sets of gripping means to cause one to take a sheet and transfer it to the second, and the second to carry the sheet in

a plane parallel to one of said surfaces into and out of the press and transfer it to the third set.

51. The combination with a press having a 5 movable press-member, an eccentric member; and a draw-bar connecting said eccentric member to said press-member; of sheet-feeding means carried by said press-member, and driving means including rotary 10 motion driving devices connecting said sheet-feeding means to said eccentric member.

52. A sheet-feeding mechanism for presses having, in combination, sheet-gripping devices having spring closing pressure means, means to impart a forward and backward movement to said sheet-gripping devices, means consequent upon said forward movement to open said sheet-gripping devices 20 against the pressure exerted by said pressure means to receive the sheet, means independent of said backward movement to cause said pressure means to be applied to grip the sheet, means subsequently to diminish said pressure, and means to take the sheet from said gripping means while the pressure is diminished and feed the sheet.

53. In a sheet feeding mechanism for presses, the combination of three sets of 30 sheet grasping means, means relatively to actuate said grasping means to cause the same successively to grasp the sheet and to transfer it from the first to the second and from the second to the third, and means for varying the extent of movement of the second set without changing the extent of movement of the first or third.

54. In a sheet-feeding mechanism for presses, the combination of a plurality of 40 sets of opening and closing sheet-grasping means, means relatively to actuate said grasping means to cause the same successively to grasp the sheet to transfer the latter from one set to another and to cause the 45 sheet to be carried into and out of the press, and means to vary the travel of the set which carries the sheet into the press while still causing the transfer from one set to another to occur always at the same point.

55. In a sheet feeding mechanism for presses, the combination of a plurality of sets of opening and closing sheet-grasping means, means to impart to one or more sets a fixed movement, means to impart to one 55 set an adjustable movement, means for causing one set to open and another set to close upon the sheet thereby to transfer the sheet from one to another, and means at will to determine the extent of movement of one set 60 from the transfer point.

56. The combination with a press having a pair of cooperating press members, of a plurality of pairs of opening and closing sheet grasping means distinct from said 65 press members, and instrumentalities rela-

tively to actuate said pairs of grasping means to cause them successively to grasp and carry the sheet and to cause one pair to feed the sheet into and withdraw it from the press.

57. A sheet handling mechanism comprising, in combination, a plurality of sheet grasping means; means relatively to actuate the same to cause one to grasp and take a sheet from the supply; means to cause a 75 second meantime to hold a previously transferred sheet in fixed position to be operated upon and subsequently deliver the same; sheet positioning means; and means to cause the first grasping means to coöperate with 80 said positioning means to position the sheet and then to transfer its sheet to the second and to receive another sheet from the supply.

58. A sheet handling mechanism comprising, in combination, three sheet grasping means; means relatively to actuate said grasping means to cause one to take a sheet from the supply while a second is holding a sheet in position to be operated on; positioning means; and means to cause the first grasping means to coöperate with said positioning means to position the sheet and subsequently transfer its sheet to the second while the third is delivering a sheet previously received from the second.

59. A sheet handling mechanism comprising, in combination, a plurality of sheet carriers; sheet positioning or alining means; means relatively to actuate said carriers to 100 cause one to carry a sheet from the supply toward a first transfer point; means to cause a second meantime to transfer to a third carrier at a second transfer point a sheet previously taken from the supply; means to 105 cause the first carrier to coöperate with said sheet positioning means to first position the sheet with relation to the second carrier and subsequently to transfer the previously positioned sheet to said second carrier at said 110 first transfer point while the third is delivering its sheet; and means to cause the second carrier to carry the positioned sheet to an operating point and to hold the sheet properly positioned to be operated upon.

60. A sheet handling mechanism comprising, in combination, a plurality of sheet grasping devices one having one or more abutments arranged for engagement with the edge of the sheet to position the latter; means to cause one of said devices to grasp the sheet; means to cause the sheet while thus grasped to be squared or positioned against said abutment or abutments preparatory for transfer; and means subsequently to cause the second device to grasp the sheet and the first device to release the sheet after the latter has been grasped by the second.

61. A sheet transferring mechanism com-

- prising, in combination, a plurality of opening and closing sheet grasping devices one provided with one or more gage stops for the edge of the sheet, and instrumentalities 5 relatively to actuate said devices to cause one to open to receive and close to grasp the sheet, and to transfer the sheet to a second, and by slipping frictional engagement with the sheet to carry the latter against the stop 10 or stops of the second.
62. A sheet handling mechanism comprising, in combination, a sheet carrying device, and positively acting means to cause said device positively to advance the sheet by 15 pushing the sheet by its rear edge, hold the sheet fixed and subsequently carry the sheet by pulling the latter by said edge.
63. A sheet handling mechanism comprising, in combination, a sheet carrying device, 20 positively acting means to cause said device positively to advance the sheet by pushing the sheet by its rear edge, hold the sheet fixed and subsequently carry the sheet by pulling the latter by said edge, and means 25 for varying the extent of movement of said carrying device.
64. A sheet handling mechanism comprising, in combination, a plurality of sheet carrying means; positively acting means to 30 cause one carrying means positively to advance the sheet, then to dwell in substan-
- tially fixed position for a certain period and subsequently transfer the sheet to a second carrying means; and means for varying the extent of movement of said second carrying 35 means while maintaining the point of transfer and the period of dwell the same.
65. The combination with a press having a movable press-member, an actuating member, and means connecting said actuating member to said press-member; of sheet-feeding mechanism carried by said press-member, and means for driving said mechanism directly from said actuating member without the intervention of said press-member. 40
66. The combination with a press having a movable press-member, a revolving actuating member, and means connecting said actuating member to said press-member; of sheet-feeding mechanism carried by said 45 press-member, and means for transmitting driving movement from said actuating member directly to said mechanism without the intervention of said press-member.
- In testimony whereof, I have signed my 55 name to this specification, in the presence of two subscribing witnesses.

WILLIAM C. GLASS.
